UNITED STATES PATENT OFFICE.

GUY F. HITCHCOCK, OF HOUSTON, TEXAS.

LANTERN.

Application filed June 1, 1926. Serial No. 112,847.

This invention relates to new and useful improvements in lanterns.

One object of the invention is to provide a lantern of the character described which has been designed for giving signals requiring lights of different colors, and is particularly adapted for use by trainmen.

Another object of the invention is to provide a lantern of the character described having a transparent colorless globe and also equipped with a colored lens which may be moved into active position, when a colored signal is required, and into inactive position when it is not desired to use said lens.

With the above and other objects in view this invention has particular relation to certain novel features of construction, operation and arrangement of parts, an example of which is given in this specification and illustrated in the accompanying drawings, wherein:

Figure 1 shows a front elevation of the lantern, partly broken away and showing the lens in active position.

Figure 2 shows a plan view of the clamp collar employed, shown partly in section.

Figure 3 shows an enlarged fragmentary view of the lens frame, and the connecting link therefor.

Figure 4 shows a side elevation of the lantern, partly broken away and showing the lens in active position, and

Figure 5 shows a side elevation thereof, partly broken away and showing the lens frame in section and the lens in inactive position.

Referring now more particularly to the drawings, wherein like numerals of reference designate similar parts in each of the figures the numeral 1 designates the base of the lantern, of conventional type, and which is provided with an upstanding annular band 2, whose upper edge has a seat

3 to receive the lower end of the glass globe 4. The numeral 5 designates a dome whose sides are perforated. This dome seats on the upper end of the globe 4 and has a crown flange, or skirt 6 and a cage-like structure 7 is secured, to this skirt and forms a guard which surrounds and protects the globe and base 1 and the bottom ring 8 of this guard forms a wide base support for the lantern. A suitable bail or

handle 9 is provided which is of an inverted U-shape and the free ends of its side arms are attached to the side brackets 10, 10, carried by the guard 7.

There is an annular open band 11 clamped around the dome 5. The free ends 12, 12, of this band are outwardly turned and a clamp bolt 13 is fitted through said ends and releasably secures said band to said dome. Upstanding from one of said outwardly turned ends 12 there is a T-bar 14 having the forwardly declining head 15 and at the opposite side of the band there is an upstanding anchor 16 whose upper end has the inside notch 18.

There is a substantially rectangular lens 70 frame 19 wherein is mounted a lens 20, of colored glass. The sides of the lens frame are formed of inwardly diverging wings 21, 21, whose free ends rest against the guard 7 when the lens 20 is in active position. 75

A link 22 is provided whose lower end is pivotally connected to the upper edge of the lens frame 19 and whose upper end is formed into a rectangular loop whose cross bar 23 works through a bearing in the T-bar 80 14 beneath the head 15. Connected to the lower edge of the lens frame there is a U-shaped link 24, the free ends of whose arms are hinged to said frame, said free ends being formed into inwardly extending 85 hooks 25, 25. The lower end of this link is formed into a hook 26 adapted to engage the ring 8, to anchor the lens in active position.

When the colored lens is to be used it is 90 anchored in active position, as shown in Figures 1 and 4. When it is not desired to use said lens the lower end of the link 24 is released from the ring 8 and the lens frame is moved upwardly and inwardly between the arms of the bail 9 and the link 22 will swing around into position underneath the lens frame, as shown in Figure 5.

One edge of the lens frame is then seated in the notch 18 and the hooks 25 engaged 100 under the corresponding ends of the head 15 and the lens frame and lens are thereby held in inactive position on the dome 5.

The lens frame and lens, and their appurtenances may be applied to any conventional type of lantern by merely securing the clamp band 11 around the dome 5, and may be removed, as a unit, by releasing

said band; all without the necessity of making any change or alteration in the lantern proper.

What I claim is:—

- 5 1. The combination with a lantern having a frame, a globe and a dome, of a band adapted to be releasably clamped, around the dome, an anchor upstanding from said band at one side, a bar upstanding from 10 the other side of said band, a lens frame and a lens capable of movement into active position in front of the globe and into inactive position above the dome, a link connecting said lens frame to said bar, a link 15 one end of which is connected to said lens frame and is formed with a hook and whose other end is formed to engage the bottom of said lantern frame when the lens is in active position, said anchor having a notch 20 to engage the edge of said lens frame and said bar having a head adapted to be engaged by said hook, when the lens is in inactive position.
- 25 2. The combination with a lantern having a frame, globe and dome, of a releasable band secured around the dome, an upstanding anchor carried by the band at one side, an upstanding bar carried by the other side of the band, a lens frame and a lens therein 30 capable of movement into active position in association with the globe and into inactive position above the dome, a link connecting said frame to said bar, a link, one end of which is connected to said frame and is formed with a hook and whose other end is formed to engage the bottom of said 35 lantern frame when the lens is in active position and means carried by said anchor and adapted to interlock with said lens frame 40 and means on said bar adapted to engage said hook when the lens is in inactive position.
- 45 3. The combination with a lantern having a frame, globe and dome, of a releasable band around the dome, an anchor upstanding from said band, at one side, provided 50 with an inside shoulder, a bar upstanding from the other side of said band, a lens frame, a lens in the frame, said frame and lens being capable of movement into active position in association with said globe and into inactive position above the dome, a link connecting said lens frame to said bar, a link 55 one end of which is connected to said lens frame and is formed with a hook and whose other end is formed to engage the bottom of the lantern frame when the lens is in active position, said shoulder being dis-

posed to engage one edge of the lens frame when the lens is in active position and means 60 carried by said bar with which said hook is adapted to engage when the lens is in said last named position.

4. The combination with a lantern having a frame, a globe and dome, of a releasable 65 band around the dome, an anchor upstanding from said band at one side, a bar upstanding from the other side of the band, a lens frame and a lens therein capable of movement into active position in front of 70 the globe and into inactive position above the dome, a link connected at one end to said bar and at its other end to one edge of said lens frame and whose other end is formed to engage the bottom of the lantern 75 frame when the lens is in active position, a hook carried by said last mentioned link, means carried by said anchor adapted to engage one edge of the lens frame when the lens is in inactive position and means carried 80 by said bar with which said hook is adapted to engage when the lens is in inactive position.

5. An attachment for lanterns including a band, upstanding members secured to the band and oppositely disposed, a lens frame and lens therein, a link connected at one end to said lens frame and at its other end to one of said upstanding members, a link 85 pivoted to the other edge of said lens frame, 90 one of said upstanding members being provided with means adapted to engage said lens frame, and means carried by the last mentioned link and adapted to engage the other upstanding member. 95

6. An attachment for lanterns comprising a band adapted to be secured around the lantern dome, oppositely disposed upstanding members secured to said band, a lens frame and a lens therein, said lens being 100 adapted to be moved into active position in association with the lantern globe, or into inactive position above said dome, a link pivoted at one end to one of said upstanding members and at its other end to said frame, a link pivoted at one end to said frame, hooks at the respective ends of said last named link, means carried by said upstanding members provided for engagement with the margin of said frame and with one of said hooks respectively, when the lens is in 110 inactive position.

In testimony whereof I have signed my name to this specification.

GUY F. HITCHCOCK.
